170,032

PHOTOGRAPHIC CAMERA

Morris Schwartz and William Castedello, Plainville, Conn., assignors to The Kalart Company Inc., Stamford, Conn.

Application December 31, 1947, Serial No. 143,462

Term of patent 14 years

(Cl. D61—1)

To all whom it may concern:

Be it known that we, Morris Schwartz and William Castedello, both citizens of the United States of America, residing in Plainville, county of Hartford, and State of Connecticut have invented a new, original, and ornamental Design for a Photographic Camera, of which the following is a specification, reference being had to the accompanying drawings, forming a part thereof.

Fig. 1 is a top view of a closed photographic camera, showing our design.

Fig. 2 is a rear view of the closed camera.

Fig. 3 is a front view of the camera in open position.

Fig. 4 is a side view of the camera in open position, and

Fig. 5 is a side view opposite to the side view of Fig. 4, showing the camera in closed position.

We claim:

The ornamental design for a photographic camera, as shown.

MORRIS SCHWARTZ.
WILLIAM CASTEDELLO.
